UNITED STATES PATENT OFFICE.

DANIEL W. BATES, OF HILLSDALE, MICHIGAN.

RAILWAY-TIE.

No. 895,413.

Specification of Letters Patent.

Patented Aug. 11, 1908.

Application filed March 13, 1908. Serial No. 420,929.

To all whom it may concern:

Be it known that I, DANIEL W. BATES, a citizen of the United States, residing at Hillsdale, in the county of Hillsdale and State of Michigan, have invented a new and useful Railway-Tie, of which the following is a specification.

This invention relates to railway ties and to means combined therewith for fastening 10 rails thereto.

The object of the invention is to provide a tie formed preferably of heavy sheet metal, the parts being assembled to produce a hollow body suitably reinforced at points 15 where it receives the weight of the rails.

A further object is to provide rail engaging devices of novel form which are secured within and extend beyond the body, said devices also constituting means for holding 20 the reinforcing or bracing elements against displacement within the tie body.

With these and other objects in view the invention consists of certain novel features of construction and combinations of parts 25 which will be hereinafter more fully described and pointed out in the claims.

In the accompanying drawings is shown the preferred form of the invention.

In said drawings: Figure 1 is a view partly 30 in elevation and partly in longitudinal section of a tie embodying the present improvements, portions of the tie being removed. Fig. 2 is a section on line A—B, Fig. 1. Fig. 3 is a detail view of one set of rail fasteners.

Referring to the figures by characters of 35 reference, 1 designates the flat base plate of the tie on which is mounted an inverted longitudinally channelled plate 2 having longitudinal outstanding flanges 3 which rest 40 upon and are riveted or otherwise secured to the plate 1. A pair of slots 4 and 5 is formed within the top portion of plate 2 near each end, the two pairs of slots being spaced apart such a distance that the fastening 45 means insertible therethrough will hold the rails at a proper distance apart. Moreover, the slots of each pair are spaced apart a distance equal to the width of the base of a rail. Keys 6 are insertible into each slot 5 for 50 filling it after the fastening means have been inserted into the tie.

An inverted substantially U-shaped brace 7 is disposed within the tie body near each end thereof, each of these braces being located between the slots 4 and 5 of each pair 55 and being of practically the same width as

the distance between said slots. The brace is held against displacement within the body by means of rail fastening devices. One of these devices consists of a metal plate 8 having an upstanding retaining flange 9 at one end while at its other end an extension 10 is formed which is designed to extend through the slot 5 and is bent inwardly as at 11 so as to bear upon and engage the inner base flange of a rail 12. Another plate 13 rests upon the plate 8 and abuts against flange 9 and this plate has an extension 14 which extends upwardly through the slot 4 and is bent to extend over and engage the outer base flange of rail 12. Registering bolt holes are formed in the two plates 8 and 13 and also in the top of the tie so that bolts 15 can be inserted therethrough for the purpose of binding the plates together. Plate 13 extends under the upper or intermediate portion of the brace 7 and it will be apparent therefore that the same constitutes efficient means for preventing displacement of the brace in any direction as is clearly indicated in Fig. 1.

In assembling the parts herein described the brace 7 is first positioned within the tie after which plate 8 is inserted through the slot 5 and under the tie top. Plate 13 is 35 then inserted through the slot 4 and the end of plate 13 is then swung upward against the top of the tie body so that they will assume the positions disclosed in Fig. 1. This movement of the parts will be permitted in view 40 of the fact that the slot 5 is of sufficient width. After the two plates 8 and 13 have been secured in position by means of the bolts 15 the key 6 can be forced downward into the slot 5 and removal of the plates 8 and 13 is thus prevented even though the bolts 15 should be withdrawn. By extending 45 the plate 8 under the brace 7 displacement of the brace is prevented. Should it be desired to remove the rail from the tie it 50 does not become necessary to remove the tie. It is merely necessary to remove the bolts 15 so that the fasteners can be detached from the tie whereupon by forcing the key 6 upwardly either or both of the fasteners can be 55 withdrawn from the tie and the rail lifted out of position. Importance is attached to the fact that the fasteners will operate to efficiently hold the rails against spreading even though the bolts 15 should become detached 60 because under these conditions it is impossible for the plates 13 and 8 to be removed.

from the tie unless the key 6 is first forced upwardly. Where the tie is used at curves a short channel iron 16 may be riveted or otherwise secured upon the bottom of the tie to prevent the same from creeping longitudinally.

What is claimed is:

1. The combination with a hollow tie body, and rail fastening devices extending therein, to and secured therein; of a tie brace within the tie body and held against displacement by said devices.
2. The combination with a hollow tie body having openings in the top thereof; of rail engaging and fastening devices insertible through the openings, those portions of said devices within the body lapping and disposed in contact, and means extending through the lapping portions of the devices and the top of the tie for binding said devices together.
3. The combination with a hollow tie body having openings in the top thereof; of a plate disposed within the body and having a rail engaging extension at one end projecting through one of the slots, a plate interposed between the first mentioned plate and tie body and having a rail engaging extension at one end extending through the other slot, and means extending through the plates and the top of the tie body for binding said plates to the body.
4. The combination with a hollow tie body having openings therein; of a plate within the tie body and having a retaining flange at one end, a rail engaging extension at its

other end and extending through the other opening, means extending through the plates and the top of the tie for binding them together, and a holding key insertible into one of the openings.

5. The combination with a hollow tie body having openings therein; of lapping plates secured within the body, said plates having rail engaging extensions projecting through the openings in the body, and a brace within the body and held against displacement by the plates.

6. The combination with a hollow tie body having openings therein; of lapping plates secured within the body, said plates having rail engaging extensions projecting through the openings in the body, and a brace seated within the body and extending between one of the plates and the top of the tie, both plates coöperating to hold the brace against lateral displacement.

7. The combination with a hollow tie body having openings therein; of lapping rail engaging devices secured within the body, and a key insertible into the tie body for preventing accidental withdrawal of said devices through the openings.

In testimony that I claim the foregoing as my own, I have hereto affixed my signature in the presence of two witnesses.

DANIEL W. BATES.
